CLAIM

The ornamental design for a suture needle-holding forceps, as shown and described.

DESCRIPTION

FIG. 1 is a front elevational view of a suture needle-holding forceps showing my new design;

FIG. 2 is a top plan view thereof;

FIG. 3 is a rear elevational view thereof;

FIG. 4 is a bottom plan view thereof;

FIG. 5 is a left side elevational view thereof;

FIG. 6 is a right side elevational view thereof;

FIG. 7 is an top plan view thereof in a opened position; and,

FIG. 8 is a left side elevational view thereof shown in use, the broken line showing on the suture needle is for illustrative purposes only and forms no part of the claimed design.
